UNITED STATES PATENT OFFICE.

JOHN W. McMANAMA, OF WALTHAM, MASSACHUSETTS, ASSIGNOR OF ONE-THIRD TO SAMUEL W. SIMONDS AND ONE-THIRD TO FRANCIS A. BARBEY, BOTH OF CAMBRIDGE, MASSACHUSETTS.

INNER RAIL FOR RAILROAD-TRACK CURVES.

1,239,927.

Specification of Letters Patent. Patented Sept. 11, 1917.

Application filed January 30, 1917. Serial No. 145,385.

To all whom it may concern:

Be it known that I, JOHN W. McMANAMA, citizen of the United States, residing at Waltham, in the county of Middlesex and 5 State of Massachusetts, have invented new and useful Improvements in Inner Rails for Railroad-Track Curves, of which the following is a specification.

This invention relates to a railroad-track 10 curve of the character disclosed by Letters Patent of the United States, No. 1,006,579, and including a curved inner rail having its tread face reduced in width from the standard size, for purposes set forth and de- 15 scribed by the specification of said patent.

The chief object of the invention is to 20 improve the design of the inner rail in such manner that first, the wear and reduction of height of the tread face, due to the grinding action of wheels thereon, will not result in any substantial increase in the width of 25 said face, and secondly, the base portion of the rail head, including the downwardly facing bearing surfaces which contact with the 30 upper edges of the angle plates connecting the ends of the rail with other rails, has a width equal to or approximating that of the base of the head of a standard rail. Another object is to otherwise improve the de- 35 sign as hereinafter pointed out.

To these ends the invention consists in the improvements hereinafter described and claimed.

The accompanying drawing is a trans- 35 verse section of a rail embodying the invention.

In carrying out my invention, I provide 40 the head 12 of the rail with a base, preferably of standard width, said base including the downwardly facing bearing surfaces 13 projecting from opposite sides of the web 14, a relatively narrow tread 15, and diversified sides characterized as follows:

Said sides include substantially parallel 45 upper portions 16 extending downwardly from the tread 15, and forming therewith the wear-sustaining portion of the rail head, the form and arrangement of said portions 16 being such that reduction of the height 50 of the tread by wear does not substantially increase its width.

Said sides also include relatively narrow lower portions 17 joining the bearing surfaces 13 and defining the width of the head

base, and intermediate portions 18 joining 55 said upper and lower portions. As here shown the intermediate portions 18 are inclined, and preferably curved, downwardly and outwardly from the portions 16 to the portions 17, said intermediate portions 60 forming fillet surfaces between said upper and lower portions.

The following are suitable dimensions of portions of the rail head:

Distance between the side portions 16, 16, 65 one and thirteen sixteenths inches.

Distance between the side portions 17, 17, three inches.

Width of side portions 17 approximately 70 one-fourth of an inch.

These dimensions may, of course, be varied.

While the side portions 17 are shown as transversely flat, they may obviously be transversely curved or convex. 75

The distance between the bearing surfaces 13 of the head and the opposed bearing surfaces 20 of the rail flange 21 is preferably the same as in a standard rail, to permit the interposition of standard angle 80 plates between said surfaces. The distance between the tread 15 and the base of the rail head is preferably greater than in a standard rail, to permit reduction of the height of the tread surface by wear, without 85 unduly sacrificing strength. This results in a height or distance between the tread and the under side of the flange which is greater than in a standard rail. This increase of height over that of a standard rail, joined 90 to the end of my improved curved rail, may be compensated for in practice by raising the standard tangent rail by means of shims, or like well known contrivances. 95

I claim:—

1. A railroad rail, the head of which has a relatively wide base, including downwardly facing bearing surfaces at opposite sides of the web, a relatively narrow tread, and sides including substantially parallel upper portions extending downwardly from the tread, and adapting the tread to be worn down without substantial increase of its width, lower portions joining said bearing surfaces, and outwardly and downwardly 100 inclined intermediate portions forming fillet surfaces between said upper and lower portions. 105

2. A railroad rail, the head of which has a relatively wide base, including downwardly facing bearing surfaces at opposite sides of the web, a relatively narrow tread, and diversified sides extending from the tread to the base, and including upper portions adapting the tread to be worn down without substantial increase of its width lower portions defining the width of the head base, and intermediate portions joining said upper and lower portions.

3. A railroad rail, the head of which has a base including downwardly facing bearing

surfaces at opposite sides of the web, and a relatively narrow tread, the distance between said bearing surfaces and the opposed bearing surfaces of the rail flange being substantially the same as in a standard rail, to admit standard angle plates between said surfaces, and the height of the rail, or the distance between the tread and the bottom of the rail flange, being greater than the standard height.

In testimony whereof I have affixed my signature.

JOHN W. McMANAMA.

Copies of this patent may be obtained for five cents each, by addressing the "Commissioner of Patents, Washington, D. C."
